Primary Examiner — Mitchell I. Siegel

(57) **CLAIM**

The ornamental design for a golf putter, as shown and described.

DESCRIPTION

FIG. 1 is a perspective view of my new golf putter design
 FIG. 2 is a top view of my new golf putter design
 FIG. 3 is a front view of my new golf putter design
 FIG. 4 is a left side view of my new golf putter design
 FIG. 5 is a right side view of my new golf putter design
 FIG. 6 is a back view of my new golf putter design; and,
 FIG. 7 is a bottom view of my new golf putter design.
 My golf putter design is characterized by the curved bottom
 that gradually slopes up, taper to the back, slot down the
 middle and overall length.
